MOUNT FOR WEB ROLLS

Robert H. Greene, Marion, Ind.

Application November 8, 1946, Serial No. 708,760

6 Claims. (CL 242—58)

1

This invention relates to improvements in a mount for web rolls adapted particularly for elevating and supporting heavy web rolls in selected positions to be unwound and fed to a processing machine.

An object of the instant invention is to afford an apparatus in which is initially received from the floor level of its situs, a heavy web roll to be subsequently elevated and adjusted into a selected position as required for unwinding of the roll while thus supported, all of which is accomplished with but little expenditure of physical effort upon the part of an operator.

Another object of the invention is to provide power-driven apparatus for handing a heavy web roll and supporting it in position for unwinding.

A further object of the invention is to construct a power - driven apparatus for handling heavy web rolls of various lengths and supporting the roll in an accurately adjusted position relative to the processing machine that receives the web from the roll.

And a still further object of the invention is the provision of a power-driven machine in which a heavy web roll is secured accurately on supports therefor and hoisted to a predetermined elevation, and manually operated means by which to bodily move the hoisting and supporting apparatus together with the web roll into selected positions.

Other objects and advantages of the invention appear in the following description.

An illustrative embodiment of the invention is shown in the accompanying drawings, in which:

Fig 1 is a side elevational view of an apparatus in which the invention is incorporated;

Fig 2 is a top plan view of the structure shown in Fig 1;

Fig. 3 is an inner end elevational view of one of the elevating and supporting stands, the base of the machine being in transverse section;

Fig. 4 is a front end elevational view of the other elevating and supporting stands;

Fig. 5 is a fragmentary end elevational view of one of the oscillators mounted on the base for the machine, the base being in section;

Fig. 6 is a detail elevational view of the manually operated adjusting mechanism, parts being broken away;

Fig. 7 is a fragmentary detail side elevational view of one of the oscillators, partially in section;

Fig. 8 is a detail side elevational view of a magnetic brake for certain of the motors;

Fig. 9 is a side elevational view of one of the roll chucks used in the machine, partially in section;

Fig. 10 is a front end view projected from Fig. 9; and

Fig. 11 is a diagram of the electric wiring for the apparatus.

2

The illustrative embodiment of the invention consists of two stands indicated generally by A and B arranged in opposing positions on a stationary base 1 upon which both stands are movable, there being provided rollers 2 secured to the stands by brackets 3 arranged so the rollers travel between the flanges of the channel rails 4 of the base.

Each stand consists of a frame having parallel uprights 5—6 connected together at their lower ends at each side thereof by side bars 7 that override the corresponding base channel rails 4 out of contact therewith. An oscillator (Fig. 7) is mounted in each of said frames consisting of

10 a head-block 8 and a tail-block 9 spaced apart from each other and connected together by divergent arms 10, each having a hub 11—12 that has bearing in the corresponding uprights 5—6 so that the oscillators are axially aligned.

15 Each of said head-blocks has a radial extension 13, on the outer end of which is secured a U-shaped frame 14, in the arms of which is mounted for rotation an arbor 15. The arbors are normally axially aligned and have on their inner ends corresponding roll-chucks 16. One of the arbors has thereon a hub 15' that is engaged by a brake-shoe 17 connected with its frame, as at 18, and which is tightened about the hub 15' by a hand-screw 19 to retard rotation of the arbor.

20 30 The stands A and B are connected together by a coupling shaft 20 that has turning movement in a pendant lug 21 on the frame for the stand A and is threaded in another lug 22 on the frame of the other stand B, so that upon turning of the shaft 20 the stand B is moved toward or from the stand A accordingly as the shaft is turned. The shaft 20 is actuated by a reversible motor C through the medium of a speed reducing gear 23 and a chain and sprocket connection 24.

35 The oscillator for each stand is individually actuated by means of a corresponding reversible motor D—E through the medium of a speed reducing gear 25, a dual chain and sprocket connection 26 including a sprocketed counter-shaft 27, that is mounted in pendant brackets 28 on the frame for the corresponding stand, and a slack chain 29, engaging the countershaft, that partially encompasses the head 8 of the oscillator, the extremities of said chain being secured to

40 45 50 the perimeter of the head by bolts 30. Provision is made for taking up the slack of the chain 29, preferably consisting of a spring-pressed sliding bar 31 on the stand structure provided with a roller 32 that bears against the chain, there being provided a screw 33 for adjustment of the take-up device.

55 Endwise travel of the stands A—B on the base is affected by mechanism consisting of a transverse shaft 34 that is suspended in brackets 35 for turning movement which has pinions 36 on its

60

ends that engage corresponding racks 37 secured on the channel rails 4 so that, upon rotation of the shaft 34, the stands are motivated on the base lengthwise. The shaft 34 is actuated by a worm 38, secured on the lower end of an operating post 39, that engages a worm-wheel 40 on the pinion shaft 34. The post is rotatably mounted in brackets 41 and 42 that are mounted respectively on the pinion-shaft 34 and the frame for the stand A, the upper end of the post having thereon a manually-operated lever 43 for turning same. As the stand A is motivated, the other stand B travels likewise through the medium of the coupling shaft 28.

Each stand A-B has connected therewith a transverse guide-way 44, by means of bars 45, the ends of which project outwardly beyond the base 1. Preferably, the guide-way is formed of two channel bars 44' spaced apart from each other to afford a slot 46. The guide-way 44 has movably mounted therein a slotted cam-plate 47 that projects up through the slot 46, and has a supporting brace a and on said channel bars are mounted stationary cam-plates 48 having braces b, the cam-plates 48 being disposed astride of the movable cam-plate. The slots 47'-48' in said cam-plates are divergent and have extending therethrough a follower-pin 49 the ends of which are connected by means of links 50 with a wrist-pin 51 that projects from the head of the corresponding oscillator. Thus, when the oscillator is rotated to loading position the cam-plate 47 is caused to travel to the position indicated in dotted lines (Fig. 3).

Each guide-way 44 has a supplemental guide-frame 52 consisting preferably of a pair of angle bars 53 that overlie the base, brackets 54 being provided for securing the guide-way and guide-frame together.

In each guide-frame 52 is disposed a traveling tray 55 in which are supported a series of idling rollers 56 that extend transversely with respect to the base 1, the tray being provided with rollers 57 that ride upon the bars 53. Each tray is connected with the corresponding movable cam-plate 47 by means of a bracket 58. Thus, the roller tray is moved in its guide-frame according to the travel of the cam-plate 47 (Fig. 3).

Preferably, the guide-frame 52 is provided with rollers 59 by which it is supported on the base channel rails, thus to permit free travel of the stand B on the base when the roller trays are loaded with the web roll.

In Figs. 9 and 10 is shown the roll chuck 16 which consists of the arbor 15 mounted for rotation in the frame 14. The outer projecting end portion of the arbor is encompassed by a concentric axially movable collar 16' provided with a series of pockets 16''. In the outer end portion of the arbor are a series of radially disposed chamfers 60 that slant convergently toward the outer end of the arbor. In each chamfer is disposed a movable jaw 61, the rear end of which has an L-shaped extension 62 that is disposed in the corresponding pocket 16'', and the forward end of the jaw has an extension 63 that protrudes into a hollow tapered tip 64 secured on the end of the arbor. Compression springs 65, disposed in the pockets 16'', bear upon the L-shaped extensions of the jaws to urge outward movement of the jaws toward closed position, and an annular series of other springs 66 are disposed around the arbor between said collar and a butt-plate 67 on said arbor that tend to move the collar toward jaw-closing position. By this ar-

rangement, when the collar is moved backward upon the arbor, the jaws expand outwardly into engaging position, guided by the extensions 62 and 63 in said pockets and tip.

5 The motors D and E are reversible and synchronized so as to rotate simultaneously clockwise or counter-clockwise, and thus the oscillators are both moved selectively into loading or supporting position (Fig. 4) accordingly as the motors are energized.

10 Each of the oscillator activating motors D-E have in connection therewith a magnetically-operated brake 68 (Figs. 1-8) provided with a solenoid 69, a brake lever 70 and shoe 71 that has frictional engagement with a drum 72 on the motor-shaft 73. The purpose of the brake is to prevent the motor from coasting while de-energized.

15 The motor C for actuating the coupling shaft 28, and the motors D-E for actuating the oscillators, are energized by current derived from a suitable source of power (not shown) through main conductors 74 and suitable intermediate electrical appliances and connections, commonly known, and exemplified in the diagram (Fig. 11). In the arrangement shown, the group of connections indicated generally by F, switches 75 and 76, normally open, are so connected that the closing of one or the other of the switches causes the motor C to rotate forward or reverse, resulting in rotation of the coupling shaft 28 and consequent movement of the stand B toward or from the stand A accordingly. The group of connections, generally indicated by G, are for the main control of the motors D and E that activate the oscillators, there being provided forward and reverse, normally open, switches 77 and 78 so connected that the closing of one or the other of said switches causes simultaneous rotation of said motor in one direction or the other accordingly, and consequent movement of the oscillators into loading or roll-supporting position.

20 Another group of connections, generally indicated by H, is for the jog control of the motor E that actuates the oscillator on the stand B by which the motor is activated, individually, and independently with respect to the motor D, thus to enable the operator to maneuver the roll chuck 16 on the stand B into alignment with the chuck on the other stand A as occasion requires. This is accomplished by selectively closing the forward or reverse switches 79-80, thus to cause turning movement of the oscillator on the stand B relative to the oscillator on the other stand A, selectively in one direction or the other accordingly as said switches are manipulated.

Operation

25 In utilizing the invention, the machine is preferably installed so the tops of the rollers 56 in the traveling trays are located approximately at the floor level of the situs so that a web roll J may readily be rolled directly from the floor onto the rollers of both trays when the trays and the oscillators are in loading position (Fig. 3) and the stands are separated from each other sufficiently to allow the roll to clear the chucks 16. After the roll has been deposited on the rollers 56 and its bore j aligned with the chucks the stand B is drawn toward the stand A by operating the motor C, whereupon the chucks enter the bore of the roll at the ends thereof, and the roll is clamped endwise between the collars 16' on the chucks, whereupon, the jaws of the chuck expand

and firmly engage the surrounding interior wall of the roll. The roll is then elevated to supporting position by closing the appropriate switch 71 or 78, as the case may be, thus causing the oscillators to simultaneously turn upon their axes. After thus elevating the roll into unwinding position, it is jockeyed into parallelism with the processing machines (not shown) that receives the web, by manipulation of the switches 79 and 80. While the stands are thus secured relatively in position by the coupling shaft 20, the position of the web roll relative to the processing machine is further adjusted by bodily moving the stands lengthwise on the base 1 in one direction or the other by manipulation of the lever 43.

The web is then unwound in the usual manner from the roll as it is drawn into the processing machine until exhausted. During the unwinding operation the brake 17 is tightened or loosened as may be required to prevent racing of the roll or vary the tension of the web between the roller and the processing machine.

The oscillators are then returned to loading position, by closing the appropriate switch 77-78, in readiness for renewal of the loading operation.

A particular advantage of the invention is that the sequence of operations required for each complete performance is accomplished expeditiously by one operator.

Variations from the particular construction above disclosed may be resorted to by the exercise of skill in the art, without departure from the spirit or scope of the invention.

What I claim is:

1. A mount for elevating and supporting web rolls consisting of a stationary base having longitudinal parallel channel rails, two stands oppositely disposed provided with supporting rollers engaging said rails, an oscillator mounted for rotary movement in each stand, the axes thereof being alined, roll-engaging chucks revolvably supported on said oscillators disposed normally upon a common axis, one of said chucks having a brake, a transverse guide-way connected with the inner end of each stand provided with movable and stationary overlapping and oppositely inclined cam-plates, links connected with said oscillators and the corresponding cam-plates whereby to actuate the movable cam-plates as the oscillators are turned, a transverse guide-frame secured to each guide-way, a tray having guided movement in each frame and secured to the corresponding movable cam-plate, a reversible motor for each stand provided with mechanism connected with the oscillator thereon to activate said oscillator, a coupling shaft mounted for rotation in one frame, having threaded connection with the other frame and provided with another reversible motor on one of said frames to actuate said coupling shaft whereby to move one stand relative to the other on said base, and rack and pinion mechanism in connection with one of the stands and the base provided with activating means therefor whereby to adjustably move said stands bodily on said base.

2. Apparatus for handling web rolls consisting of two opposing wheeled stands mounted on a common base, oscillators mounted in said stands axially alined and provided with individual reversible motor-driven mechanism whereby to activate said oscillators, roll-engaging chucks eccentrically disposed on said oscillators, transverse guide-ways respectively connected with said stands, each provided with stationary and move-

ble cam-plates, a connection between the corresponding oscillator and cam-plates whereby to activate the movable cam-plate, transverse guide frames connected with said guide-ways, roller trays having guided movement in said guide frames and connected with the corresponding movable cam-plates, the arrangement being such that the roller trays and the chucks are moved into loading position simultaneously, or reversely 10 moved accordingly as the oscillators are turned, a revolvable coupling shaft supported in one stand having threaded connection with the other stand and provided with activating means therefor whereby to relatively adjust said stands lengthwise on the base, a gear mechanism connecting one of said stands and said base provided with activating means by which said stands are bodily adjusted lengthwise on the base, and switch-controlled electrical connections for energizing the 15 motors for said mechanisms collectively, or one of said stands independently.

3. Apparatus for handling web rolls consisting of a base, two wheeled stands oppositely disposed on said base for lengthwise movement thereon, a threaded coupling shaft connecting said stands provided with activating means whereby to move one stand on the base relative to the other, a gear mechanism on one of said stands operatively connected with said base, and having actuating means therefor whereby said stands are bodily adjusted lengthwise on said base, alined oscillators mounted respectively in said stands provided with individual motors and connected mechanisms for activating said oscillators, opposing web roll-supporting chucks on said oscillators, a transverse guide-way and guide-frame in connection with each stand, movable and stationary cam-plates on each guide-way having an operative connection with the corresponding oscillator whereby to activate the movable cam-plate as the oscillator is turned, a tray having rollers therein mounted in the guide-frame and connected with the corresponding movable cam-plate whereby the trays are automatically moved 40 into loading position when the oscillators are turned to a selected position, and switch-controlled electrical means for energizing said motors simultaneously or one of said motors independently.

4. An apparatus for handling web rolls, a pair of stands movably mounted upon a supporting base provided with alined oscillators having individual activating means therefor, opposing web roll chucks carried by said oscillators, transverse 55 guide-frames in connection with each stand provided with a roller tray having guided movement therein, a mechanism connected with each tray and the corresponding oscillator whereby the trays are moved automatically into loading 60 position when the oscillators are turned to selected positions, a coupling shaft having actuating means therefor operatively connecting said stands by which to adjust same relatively toward or from each other on said base, a gear mechanism on one 65 of said stands operatively connected with said base and having actuating means therefor whereby said stands are bodily adjusted lengthwise on said base, and electrical means for simultaneously energizing the motors for said activating means or one of said motors independently whereby to elevate the web roll to unwinding position or aline said chucks.

5. Web roll handling apparatus consisting of a pair of opposing stands mounted on a base for lengthwise movement thereon, provided with

aligned oscillators having opposing roll chucks supported thereon respectively, a coupling shaft connecting said stands having activating means therefor to adjustably move one of said stands relative to the other lengthwise on said base, a gear mechanism carried by one of said stands and operatively connected with said base adapted to adjustably move said stands bodily on said base, individual activating means for each oscillator consisting of a reversible motor and chain sprocket mechanism connecting the motor with the corresponding oscillator whereby to turn said oscillators from one selected position to another, and switch-controlled electrical connections arranged for simultaneously energizing said motors 15 or one of said motors independently.

6. In a web roll handling apparatus, two opposing stands movably mounted on a base, means for moving said stands on the base toward and from each other, axially aligned oscillators in said stands each having a head and provided with roll-engaging and supporting means movable into loading or unwinding position accordingly as the oscillators are turned, activating means for said oscillators each including a reversible motor, a slack chain partially encompassing the head of the corresponding oscillator and having a sprocket and chain connection with said motor whereby the oscillator is turned upon its axis

as the motor is revolved, a magnetic brake mechanism for each motor operable when the motor is de-energized to prevent coasting thereof, and switch-controlled electrical means having connection with said motors arranged to simultaneously energize said motors for forward or reverse movement selectively whereby to turn the oscillators to loading or unwinding position or to energize one of said motors independently for movement in either direction, and mechanism having activating means therefor connected with one of the stands and the base adapted to adjustably move said stands bodily on said base.
